SHUTTERING FOR USE IN THE MANUFACTURE OF CONCRETE STRUCTURES

Robert Mackie, Glasgow, Scotland

Application July 13, 1949, Serial No. 104,495
In Great Britain July 15, 1948

3 Claims. (Cl. 25—131)

1

This invention relates to shuttering for use in the manufacture of concrete cavity walls and is a further development of that described in the specification of my prior British Patent No. 612,490.

The prior construction of shuttering includes panels flanged along their vertical edges, uprights adapted to receive the flanged edges of the panels, separators in the concrete-receiving space to hold the uprights apart, and withdrawable distance pieces to hold apart the uprights supporting the panels in the cavity.

An object of the present invention is to provide an improved construction permitting the insertion of permanent wall-ties before the concrete is poured and eliminating the separators.

In shuttering according to the invention a vertical edge face of each of the uprights for supporting the panels forming the faces of the cavity is formed with wall-tie receiving notches, and filling pieces are pivoted to each of said uprights, each of said filling pieces being engageable with a respective notch, the filling pieces being so proportioned that, when they engage the respective notches fully, there is a gap between the bottom of each notch and the adjacent face of the respective filling piece; all of the uprights and the distance pieces are formed with transverse slots, the slots in adjacent distance pieces and uprights being adapted to register to form passageways when the shuttering is assembled; and there are provided gauge bars notched in accordance with the desired spacing of the uprights and distance pieces and each adapted to be inserted through a respective passageway, the notches being engageable with the lower edge portions of the slots in the uprights and in the distance pieces.

Locking means may be provided to hold the gauge bars in place. Said locking means may be locking bars each inserted in a passageway along the face of the associated gauge bar remote from the notched face, whereby to prevent the gauge bar from being withdrawn.

Optional additional locking means to hold the gauge bars in place comprise locking bars inserted through transverse slots at the ends of the gauge bars, said locking bars abutting against the outer faces of the outer uprights of the shuttering.

A practical embodiment of the invention is illustrated in the accompanying drawings in which Fig. 1 is a section through a horizontal plane of a portion of the shuttering of the type referred to incorporating the improvements ac-

2

cording to the present invention. Fig. 2 is a section through 2—2 in Fig. 1, and Fig. 3 is a section through 3—3 in Fig. 1.

In the drawings 1 denotes panels flanged at 2, the flanges of the panels forming the faces of the cavity being cut away to clear the wall ties to permit the panels to be withdrawn after the wall ties are in position. 3 denotes T-shaped uprights, 3A denotes uprights supporting the panels forming the faces of the cavity, 4 denotes keys, 6 denotes distance pieces, 7 denotes the concrete-receiving spaces, shown partly filled with concrete, 9 denotes an angle piece at the outside of a corner, and 10 denotes the upright at the inside of a corner. 11 denotes a metal strip linking the uprights 2. 12 denotes a wall-tie receiving notch formed in a vertical edge face of each of the uprights 3A. 13 denotes a filling piece pivoted at 14 to an associated upright 3A and engageable with an associated notch 12. 15 denotes a wall-tie resting in the gap presented between the bottom of the notch 12 and the adjacent face of the filling piece 13. 16 denotes transverse slots in the uprights 3, 3A and 10, and in 25 the distance pieces 6, said slots being in register to form a passageway when the shuttering is erected. 17 denotes a gauge bar notched at 18 to engage the lower edges of the slots 16 and hold the uprights 3, 3A and 10 the required distance apart. 19 denotes a locking bar inserted in the passageway formed by the registering slots 16 after the gauge bar 17 has been placed in position. 20 denotes additional locking bars formed with an abutment at each end and engaged in 30 transverse slots 21 at the ends of the gauge bar 17, said additional locking bars 20 abutting against the uprights 3 and 10. A key 22 is inserted behind each additional locking bar 20, to hold said bar 20 in place, the abutments on the bar engaging the adjacent upright and preventing the bar from being withdrawn.

In practice, the uprights 3 and 3A with the corner upright 10 and the distance pieces 6 are erected, and gauge bars 17 are inserted through 45 the slots 16 and the locking bars 19 put in place, thereby holding the uprights 3, 3A and 10, and the distance pieces 6 in the desired spaced relation. The filling pieces 13 are swung about their pivots 14 away from the notches 12 and wall-ties 15 are inserted in the notches, after which the filling pieces 13 are swung back to engage the notches 12, thereby holding the wall-ties 15 in place, the ends of the wall-ties 15 projecting into the concrete-receiving space. The panels 55 1 are now fitted to the uprights 3, 3A and 10.

Withdrawable distance pieces being inserted if necessary to hold the panels forming the faces of the cavity against the associated uprights.

Concrete is poured into the concrete-receiving spaces 7, and when it is set all of the outside panels 1 are removed. The locking bars 19 are next removed and the additional locking bars 20, where used, are also removed. The gauge bars 17 are now withdrawn from the slots 16. The distance pieces 6 are next withdrawn, the inside panels 1 are removed and each upright 3A in the cavity is moved along the cavity in the direction away from the wall-ties 15 carried by said upright. As the ends of the wall-ties are embedded in the concrete of the wall, the ties remain stationary and sidewise movement of the respective upright 3A causes the filling pieces 13 pivoted thereto to come against the stationary ties and to swing about the pivots 14 away from the upright. Each upright 3A can thus be completely disengaged from the associated wall-ties 15, and can be withdrawn from the cavity. It only remains to plug with cement or concrete the slots in the concrete walls left by the gauge bars, and the wall is complete.

I claim:

1. Shuttering for use in manufacturing a cavity wall, including panels flanged along their vertical edges, uprights in the cavity in the formation of the wall, said uprights being adapted to receive the flanged edges of said panels, each upright having a vertical edge face formed with notches, withdrawable distance pieces to hold said uprights apart, filling pieces pivoted to each of said uprights and each engageable with a notch of the respective upright, each filling piece being so proportioned that, when it is fully engaged with the respective notch, there is a gap between the bottom of said notch and the adjacent face of the filling piece, all said uprights

and said distance pieces being formed with transverse slots, the slots in adjacent uprights and distance pieces when in register forming passageways through the assembled shuttering, and gauge bars each having a face notched in accordance with the spacing of said uprights and said distance pieces, each gauge bar being adapted to be inserted through a respective passageway, the notches in said gauge bars being engageable with the lower edge portions of the slots in said uprights and in said distance pieces.

2. Shuttering as claimed in claim 1, including locking bars each adapted to be inserted in the passageway along the face of an associated gauge bar remote from the notched face of said gauge bar.

3. Shuttering as claimed in claim 1, including outer uprights adapted to support the panels forming the outer faces of the wall in which the gauge bars are formed with transverse slots, and locking bars are insertable in said slots, said slots being so located that said locking bars abut against the outer faces of said outer uprights.

ROBERT MACKIE.
